[57] ABSTRACT

A laminar-flame burner having a burner body with a head consisting of two halves and clamped with spacer against an aerosol chamber to define a pair of flame slots, the aerosol chamber being fed by a tube extending into the chamber from below.

**LAMINAR FLAME SEPARATE AEROSOL BURNER
FOR USE IN ATOMIC ABSORPTION
SPECTROSCOPY**

Long-path burners employed in Atomic Absorption Spectroscopy are generally attached to a spray chamber with a built-in pneumatic, ultrasonic or other type of nebulizer. The construction of these burners is such that the fuel, the flame support gas (air or N₂O), and the nebulized solution are mixed together in the spray chamber, which is connected to the burner. With such a burner, the generation of a high-temperature long-path (5 to 10 cms.) laminar flame (air + acetylene gas, N₂O + acetylene gas) is made possible. The sample in the form of a solution is transformed into fine droplets by means of the pneumatic or ultrasonic nebulizer and is mixed with the flame gases in the spray chamber and burner. The concentration of the solution in the flame which affects the sensitivity of the method depends on the nebulizer efficiency.

The previously described or known long-path laminar-flame burner uses a simultaneous supply of the three media, i.e. fuel gas, flame-support gas and dispersed solutions, into the common spray chamber and through an intermediate tube into the burner provided with a common flame gas orifice. This burner has the disadvantage in atomic absorption measurements that the quantity of the dispersed solution to be analyzed that reaches the flame gas orifice varies according to the type of the flame gas mixture employed. For example, the concentration of the dispersed solution in the flame is diminished if nitrous oxide is used instead of air as a flame support gas.

In addition, independent control of the flame and aerosol parameters is not possible in the known atomic absorption laminar flame burners where the three media are directed together into the burner, i.e. the dispersed solution to be analysed, fuel gas and flame support gas.

The object of the invention is to provide a burner which is free from the previously mentioned disadvantages of the presently used long path laminar flame burners and provides a considerable improvement in the sensitivity of the determination.

SUMMARY OF THE INVENTION

This object is achieved by constructing a laminar flame separate aerosol injection burner for atomic absorption measurements. The burner of the invention consists of a body in the form of a tube-like chamber, which is connected to the flame gas supply. A small aerosol chamber is fixed inside the burner body and is provided with a tube for connection to the aerosol supply on one side and a plurality of small orifices posi-

tioned in a line on the other side. These orifices lie between two parallel slots on the top of the burner, which slots serve as an outlet for the flame gases. In this manner the aerosol and the flame gases are completely separated. Both phases - the flame gas mixture and the dispersed solution - come into contact as a flame and an aerosol stream after passing through the separate orifices.

BRIEF DESCRIPTION OF THE DRAWING

The above and other objects will become more readily apparent from the following description, reference being made to the sole FIGURE of the accompanying drawing which is a perspective view, partly broken away, of a burner according to the invention.

SPECIFIC DESCRIPTION

From the drawing the main parts of the new atomic absorption burner can be seen. Aerosol chamber 1 is connected by the tube 11 to the aerosol supply. On the top there is a plurality of orifices 12 which direct the aerosol into the flame. The aerosol chamber 1 is mounted inside the burner in such manner as to enable the aerosol to be injected into the middle of the flame that burns between two parallel slots 22, the width of which is determined by four metal spacers 4. The spacers 4 are clamped between the aerosol chamber 1 and both halves of the burner head 3. The burner head 3 is water-cooled. Two pairs of pipe connections 31 serve as junctions to the water supply and drain respectively. Two parallel channels 32 drilled in both halves of the burner head 3 and fitted with pipe connections 31 allow the water to circulate. The burner head 3, together with the aerosol chamber 1, are fixed tightly to the burner body 2 by means of screws 5. In this manner two parallel slots 22 are formed for the flame gases which enter the burner through the inlet tube 21.

What we claim is:

1. A laminar-flame separate-aerosol-injection burner for use in atomic absorption spectroscopy, comprising an aerosol chamber provided with a plurality of orifices on the upper side and connected by a tube to an aerosol supply, said aerosol chamber being positioned inside a burner body and clamped between two halves of a burner head which are screwed tightly to the top of the burner body, and that four thin metal spacers are placed between the aerosol chamber and the halves of the burner head to form on both sides of the orifices two parallel slots for the flame gases, whereat two parallel channels are drilled on each side of the burner head connected by pipe connections to a water supply and drain respectively.
